Ass'ty.

UNITED STATES PATENT OFFICE.

ELIAS BECKER, OF PITTSBURG, PENNSYLVANIA.

SPEAKING-TUBE.

SPECIFICATION forming part of Letters Patent No. 356,091, dated January 18, 1887.

Application filed September 10, 1886. Serial No. 213,263. (No model.)

To all whom it may concern:

Be it known that I, ELIAS BECKER, a citizen of the United States, residing at Pittsburgh, in the county of Allegheny and State of Pennsylvania, have invented certain new and useful Improvements in Speaking-Tubes; and I do hereby declare the following to be a full, clear, and exact description of the invention, such as will enable others skilled in the art to 5 know which it pertains to make and use the same, reference being had to the accompanying drawings, which form a part of this specification.

My invention relates to an improvement in speaking-tubes, the object being to provide a 15 means whereby conversation may be held with any number of separate rooms through but one main tube with several branches; and with this end in view my invention consists in certain details of construction and combination 20 of parts, as will be fully described hereinafter.

In the accompanying drawings, Figure 1 is 25 a front elevation of my improved speaking-tubes, constructed in accordance with my invention, partly shown in section to show the inner working parts. Fig. 2 is a plan view of ratchet-wheel and pawl used for stopping the tubes in the exact position required. Fig. 3 is a side elevation of the same. Fig. 4 is a 30 plan view of the perforated disk which connects the several branch tubes leading to the different rooms on the one floor. Fig. 5 is a sectional view of the plate over the chamber, showing the position of the branch of the main tube when at rest.

To put my invention into practice and give 35 the same bodily form, I erect a vertical tube, *a*, from the ground-floor, having an ordinary speaking-tube mouth-piece, *b*, attached to the lower end. Attached to this tube *a*, a short 40 distance above the floor of the second story of the building, is a funnel-shaped air-tight chamber, *c*, over which is rigidly secured a plate, *d*, having a number of circular openings, *e*, through the same. Secured in these openings 45 *e* are a number of branch tubes, *f*, each leading to separate rooms on the same floor. Attached to the main tube *a* is a short branch tube, *g*, having a rubber bearing, *h*, at the top or place of connection with the perforated 50 plate *d*. A small spiral spring, *i*, placed below this rubber ring *h*, serves to press the

same tightly against the plate *d*. A short distance above the floor of the third story I arrange a similar perforated plate, *d*, and chamber *c*, having a suitable number of branch 55 tubes, *f*, connecting the several rooms on that floor. This arrangement I continue until the top floor, together with all the rooms of the building, is connected to the main tube *a*.

Below the first funnel-shaped chamber, *c*, I 60 place a ratchet-wheel, *j*, and pawl *k*. This ratchet *j*, I construct with the same number of teeth *l* as the building in which the apparatus is placed has rooms. On the top of this wheel *j*, and integral therewith, is a drum, *m*, 65 of less diameter than that of the ratchet *j*. A stop or starting projection, *n*, is also attached to this elevated drum *m*. At the front of this projection *n* is attached an inclined piece, *o*, which, when the ratchet has made a single revolution, lifts the pawl *k* out of the tooth, and pressed by a spring, *p*, against the drum *m*, which offers no resistance, and allows the ratchet *j* to revolve by weight or power back 70 to its original position, and stopped by the projection *n*. The pawl *k* now falls a short distance, and is ready to again engage with the ratchet *j*. Below this ratchet-wheel *j*, I place a small weighted drum, *q*, having a cord, *r*, wound about the same, to one end of which I 75 secure an indicator, *s*, and handle *t*. To the other end of this cord *r*, I attach a heavy weight, *u*, to reverse the tube *a*. To each of the chambers *c*, I attach a small tube, *v*, leading to a pair of stationary bellows, *x*, having a cord, *z*, 80 attached to the handle, and carried to the first floor, or to any part of the building, and provided with a handle, *z'*.

At each of the different stories of the building I attach to the main tube a small rubber 85 tube, *y*, having a mouth-piece, *b*, secured to one end. With this arrangement a person on either of the upper floors of the building may call the office below, or talk to any room in the building.

In operation the office or room connected directly with the main tube *a* may at any time call each or any room in the building and hold 90 private conversation with the party at the tube. Should the operator below want room No. 6, 95 the indicator *s* is drawn down to that number, which operation revolves the drum *q*, the 100

main tube *a*, and ratchet *j*, the pawl *k* entering the sixth notch of the wheel *j*. This revolution brings the branch tube *g* in the chamber *c* immediately below the tube or connecting-pipe 5 *f* of room No. 6. When the conversation is finished, the operator draws the indicator *s* down its full extent, which brings the pawl *k* a short distance beyond the twelfth notch, *l*, of the wheel *j* and raises the pawl *k*, at which 10 time the ratchet revolves back to its original position.

In case of a fire in the building, the cord *z*, attached to the bellows *w*, is drawn down, which fills all the chambers *c* and branch tubes *f* with 15 sufficient air to sound every mouth-piece *b* in the building provided with a whistle.

By placing a pulley or drum, *q*, and indicator *s* on each of the different floors of the building, communication may be held with 20 each and every room separately, in the same manner as before described.

At Fig. 5 on the drawings I have shown the position of the branch *g* of the main tube *a* when the same is at rest. Above the mouth 25 of the branch *g* is a cavity, *x'*, which allows the sound or air to enter the same when the main tube *a* is at rest.

Having thus described my invention, what I claim, and desire to secure by Letters Patent, 30 is—

1. The combination, in a speaking apparatus, with a main rotatable tube carrying branch pipes, of pipes leading to certain predetermined points and adapted to communicate with the said branch and main pipes when the said main pipe has been rotated, substantially as specified.

2. The combination, in a speaking apparatus, of a main rotatable tube, air-tight compartments arranged on the said tube and having branch tubes therein, and branch pipes leading to certain points and adapted to communicate with the said tubes in the compartments, substantially as specified.

3. A speaking apparatus having a main tube carrying a drum and a ratchet, as described, in combination with branch pipes leading to certain points and adapted to form communication with the main tube when the latter has 45 been rotated, or partially rotated, substantially as specified.

4. The main rotatable speaking-tube carrying a ratchet, in combination with an indicator and a series of branch pipes, as described, whereby communication may be formed between the main pipe and any desired branch 55 of the series, as set forth.

5. The combination, in a speaking apparatus, with the main rotatable pipe, of the air-tight chambers secured thereon, and the pipes 60 *g*, arranged therein and communicating with the said main pipe, and the branch pipes leading to various compartments in a building and adapted to communicate with the pipes 65 in the said compartments when the main pipe has been rotated, substantially as specified.

6. In a speaking apparatus, a main rotatable pipe, in combination with the branch pipes adapted to communicate therewith, as described, and an auxiliary tube or mouth-piece 70 connected with the main tube, substantially as specified.

7. The combination, in a speaking apparatus, with the main tube and branch tubes, as described, of a supplementary tube connected with the main tube, and an air-forcing device connected with the supplementary tube, 75 substantially as specified.

8. The combination, in a speaking apparatus, with the main rotatable tube, of the 80 closed chambers surrounding the same at points, as described, and having the cover *d*, the disk *h*, and flange *i*, the branches *g* in the said chambers, and the branches *f*, adapted to communicate therewith, substantially as specified.

9. The combination, in a speaking apparatus, with the main speaking-tube having air-tight chambers around the same and branch tubes leading therefrom, of a supplementary 90 tube connecting the said chambers, and a bellows communicating with the said supplementary tubes, whereby all of the pipes may be filled with air to signal, substantially as and for the purposes specified.

ELIAS BECKER.
